By his Atty.

UNITED STATES PATENT OFFICE.

HENRY A. WEIHMANN, OF PHILADELPHIA, PENNSYLVANIA, ASSIGNOR TO
SIMONS, BROTHER & CO., OF SAME PLACE.

DESIGN FOR A CANE OR UMBRELLA HANDLE.

SPECIFICATION forming part of Design No. 19,965, dated July 1, 1890.

Application filed April 15, 1890. Serial No. 348,095. Term of patent 3½ years.

To all whom it may concern:

Be it known that I, HENRY A. WEIHMANN, a citizen of the United States, residing in Philadelphia, in the county of Philadelphia and State of Pennsylvania, have invented and produced a new and original Design for Cane or Umbrella Handles, of which the following is a specification, reference being had to the accompanying drawing, forming part 10 thereof.

In the drawing is shown a side elevation of a cane or umbrella handle illustrating my new design.

A is the body part, and has an enlarged upper portion C, terminating in a rounded head B. The lower part of C and the upper part of A are drawn in, terminating in an annular band D of plain surface, and the said parts A and C, adjacent to the annular band, 15 are ornamented, as indicated at E. The body parts of A and C are of plain surface. The

lower part of A terminates in the base F, which is bounded at the upper part by an annular band G and at the lower part by an annular band I, both of plain surface. Between 25 the band G and the body A is an annular band of ornamental work H. The base part F may be ornamented substantially as shown.

The handle is made of any suitable material.

Having now described my new design, what I claim as new, and desire to secure by Letters Patent, is—

The design for cane or umbrella handles, substantially as herein described and shown. 35

In testimony of which invention I have hereunto set my hand.

HENRY A. WEIHMANN.
